[57] CLAIM

The ornamental design for a grill, as shown and described.

DESCRIPTION

FIG. 1 is a perspective view of a grill showing my new design.

FIG. 2 is a front view thereof;

FIG. 3 is a left side view thereof;

FIG. 4 is a right view thereof;

FIG. 5 is a rear view thereof;

FIG. 6 is a top view thereof; and,

FIG. 7 is a bottom view thereof.

The broken lines in the views shows environmental features
which are for illustrative purposes only and form no part of
the claimed design. The broken lines which define the
bounds of the claimed design form no part thereof.
